UNITED STATES PATENT OFFICE.

WILLIAM E. STEVENS, OF NEW HAVEN, CONNECTICUT, ASSIGNOR TO SARGENT & COMPANY, OF SAME PLACE.

DESIGN FOR COFFIN-TRIMMINGS.

SPECIFICATION forming part of Design No. 21,360, dated February 23, 1892.

Application filed January 27, 1892. Serial No. 419,474. Term of patent 14 years.

To all whom it may concern:

Be it known that I, WILLIAM E. STEVENS, of New Haven, in the county of New Haven, and State of Connecticut, have invented a new

5 Design for Coffin-Trimmings, (Case B); and I do hereby declare the following, when taken in connection with accompanying drawing and the letters of reference marked thereon, to be a full, clear, and exact description of the 10 same, and which said drawing constitutes part of this specification, and represents a face view.

This invention relates to a design for coffin-trimmings, with special reference to the 15 name-plate or handle-plate; and the design consists in the configuration and ornamentation as shown in the accompanying illustration.

Upon one side at the center a panel *a* is 20 represented as formed by two branches of scroll-work, and upon the panel is the representation of a rose with leaves forming the ground-work for the panel. At the right of the panel *a* branches extend, forming a scroll 25 at the angle, and from the left of the lower branch of the panel scroll-work is represented as running around the upper angle

and downward across that end. Upon the side opposite the panel *a* is the representation of a similar panel *b* near one end, the 30 surface of the panel being ornamented in a similar manner to that of the panel *a*. The scroll-work which extends around the end, as just described, meets corresponding branches from the upper branch of the border of the 35 panel *b*, and at the opposite end of the panel a similar branch extends to the right in a serpentine line into a scroll at the angle, which angle-scroll branches on the end of the plate to meet the corresponding scroll springing 40 from the scroll-work above, all as shown in the accompanying illustration.

I claim—

The herein-described design for coffin-trimmings, as shown in the accompanying illustration. 45

In testimony whereof I have signed this specification in the presence of two subscribing witnesses.

WILLIAM E. STEVENS.

Witnesses:

ELLIOTT LITTLEJOHN,
WILLIAM S. COOKE.
